UNITED STATES PATENT OFFICE.

LEVI H. FORD, OF ABILENE, KANSAS.

ELECTRIC SWITCH.

1,174,974.

Specification of Letters Patent. Patented Mar. 14, 1916.

Application filed February 13, 1915. Serial No. 7,981.

To all whom it may concern:

Be it known that I, Levi H. Ford, a citizen of the United States, residing at Abilene, in the county of Dickinson and State of Kansas, have invented new and useful Improvements in Electric Switches, of which the following is a specification.

The present invention relates to means for operating electric switches, and particularly those of the type having a swinging knife contact member.

One of the primary objects of the invention is to provide means whereby the switch can be actuated from different points, and in this respect it is particularly useful in a shop where a series of operations are carried on, in saving the time of the operatives.

Another and important object is to provide operating means that will insure the proper contacting of all the elements simultaneously.

The preferred embodiment of the invention is illustrated in the accompanying drawings, wherein:

25 Figure 1 is a view diagrammatic in its character and illustrating the switch and an arrangement of the operating means therefor. Fig. 2 is an enlarged view of the switch mechanism and its actuating means. 30 Fig. 3 is a front elevation of the same. Fig. 4 is a detail perspective view of the actuating yoke. Fig. 5 is a detail perspective view of one of the posts for said yoke.

Similar reference numerals designate corresponding parts in all the figures of the drawings.

An electric switch of any well known type may be employed, and in the embodiment disclosed, such a switch is illustrated as having a base 6, spring contact elements 7, and a swinging knife contact member comprising blades 8 that are movable into and out of engagement with the elements 7, and are each pivotally mounted on the base at one end, as illustrated at 9. The opposite ends of the blades 8 are connected by a cross bar 10 of insulating material. Instead of the usual handle, this cross bar has secured to it, a metal bar 11 terminating in reduced 45 50 pintles 12.

Located on opposite sides of the switch, and preferably secured to the same wall or other support as that on which the base 6 is mounted, are posts 13 having feet 14, by means of which they are secured in place. An actuating yoke 15 is J with

spaced substantially parallel arms 16 pivoted as shown at 17 to the posts, and these arms have in their free ends longitudinal slots 18 in which the pintles 12 of the cross bar 11 are slidably engaged. The yoke, furthermore, has an oppositely extending curved or angularly disposed arm 19 terminating in an eye 20. It will be evident that this yoke and arm 19 may be considered as a lever fulcrumed between its ends, one end being engaged with the knife contact member and the opposite end constituting the actuating arm. It will be evident that if this lever is moved in one direction, the switch will be thrown to open position, and if moved in the opposite direction, it will be thrown to closed position. Moreover, because of the spaced connections between the yoke and the knife member and the spaced mountings for said yoke, there can be no twisting action during the movement of the knife member, and all the blades thereof will be brought simultaneously and firmly into coaction with the contact elements 7. This structure, furthermore, may be employed in connection with electrical apparatus which it is desired to place in operation and to stop at different points. Ordinarily, a switch is employed at some point more or less contiguous to the machine to be controlled thereby, and every time such machine is to be thrown into operation the operative must go to the switch and close it. In like manner, when the machine is to be stopped, another trip is necessary to the switch. With the present operating device, means may be employed for actuating the switch from different points, and attention is called to Fig. 1 showing, diagrammatically, spaced forges A with an electrically operated trip hammer B between them. As is well known, an operator may be employed at each forge and the trip hammer is used commonly and alternately by them. There is illustrated a cord, cable or other flexible member 21, which is connected to the eye 20, and passes around a pulley 22 located beneath the switch, thence two cords, as 23, run to and over other pulleys 24 suspended from the ceiling or other suitable support, and these cords are brought to a point adjacent to the two forges, respectively, where they are provided with suitable hand grips 25 that also constitute counterweights for maintaining the cords relatively taut. Another cord or

cable 26, likewise secured to the eye 20, passes directly over a pulley 27 above the switch and to a point adjacent to the trip hammer B where another combined handle 5 grip and counterweight 28 is provided. With this arrangement, it will be evident that a workman at either forge can start the hammer whenever his iron is in proper condition to work on it, and by the time 10 he steps from the forge to the hammer, the latter is in operation. When he has completed his work, he can throw the switch out and thus stop the hammer without leaving the latter. In this operation, therefore, he eliminates two trips to the switch block, one of which would have been made with his work in his hands. It will be evident that the above is merely an example of an arrangement that can be employed 15 and that others of an analogous character can be provided with the structure disclosed.

From the foregoing, it is thought that the construction, operation and many advantages of the herein described invention will be apparent to those skilled in the art without further description, and it will be

understood that various changes in the size, shape, proportion and minor details of construction may be resorted to without departing from the spirit or sacrificing any of the advantages of the invention.

Having thus fully described my invention, what I claim as new and desire to secure by Letters Patent, is:—

In apparatus of the character set forth, 35 the combination with an electric switch including a swinging knife contact member, of a transverse bar secured to said member and having terminal pintles, posts located on opposite sides of the switch, a yoke having spaced arms pivoted to the posts and having slots in which the pintles are engaged, and an actuating arm carried by the yoke.

In testimony whereof I have hereunto set 45 my hand in presence of two subscribing witnesses:

G. A. ROGERS,
G. W. REES.

LEVI H. FORD.
